UNITED STATES PATENT OFFICE.

FRANK J. BERBERICH, JR., OF BROOKLYN, NEW YORK.

CASE FOR CLINICAL OR OTHER THERMOMETERS.

SPECIFICATION forming part of Letters Patent No. 733,536, dated July 14, 1903.

Application filed August 13, 1902. Serial No. 119,486. (No model.)

To all whom it may concern:

Be it known that I, FRANK J. BERBERICH, Jr., a citizen of the United States, residing at Brooklyn, in the county of Kings and State of New York, have invented certain new and useful Improvements in Thermometer-Cases, of which the following is a full and complete specification, such as will enable those skilled in the art to which it appertains to make and use the same.

The object of this invention is to provide an improved case for clinical and other thermometers which are provided with an enlarged head whereby the said thermometer may be readily removed in case of breakage or for sterilization or for any other purpose and whereby the said thermometer may be firmly held in position in the said case without the use of wax or other like material, a further object being to provide a thermometer-case of the class hereinafter described and claimed whereby the operation of removing the cap of the said case from the body part thereof may be accomplished without danger of loosening or breaking the said thermometer.

The invention is fully disclosed in the following specification, of which the accompanying drawings form a part, in which the separate parts of my improvement are designated by suitable reference characters in each of the views, and in which—

Figure 1 is a view of my thermometer-case closed; Fig. 2, a view of the cap thereof removed from the body portion of said case; Fig. 3, a longitudinal section of Fig. 1, and Fig. 4 a section on the line 4 4 of Figs. 1, 2, and 3.

In the practice of my invention I provide a body portion *a* of any suitable material, which is preferably cylindrical in shape and provided with an internal screw-thread *a*² at its inner or open end, and passing into and engaging the screw-thread *a*² is a corresponding screw-thread *b* on the outer surface of a neck portion *b*² of a cap *b*³, and the neck portion *b*² is also provided with an internal thread *b*⁴. I also provide a sleeve *c*, which is preferably cylindrical in form and slightly shorter than the cap *b*³, and the sleeve *c* is provided with an external screw-thread *c*², adapted to engage the internal screw-thread *b*⁴ of the neck

portion *b*² of the cap *b*³, and said sleeve is also provided with a milled flange *c*³ at the outer or larger end thereof. The inner or smaller 55 end of the sleeve *c* is provided with a plurality of longitudinal slots or recesses *d*, by means of which a plurality of leaves *d*² are formed, as plainly shown in Fig. 4, and these leaves *d*² are adapted to engage the enlarged 60 head *e* of a thermometer *e*², which passes through said sleeve, as plainly shown in Figs. 3 and 4.

In the operation of my invention the thermometer *e*² is passed through the sleeve *c*, so 65 that the head *e* rests upon the ends of the leaves *d*² of said sleeve, and the sleeve *c* is then screwed into the cap *b*³ by means of the milled flange *c*³, and when the head *e* of the thermometer *e*² strikes against the end of the 70 cap *b*³ and the sleeve *c* being still revolved the leaves *d*² are forced apart and hold the thermometer *e*² by means of the head *e* firmly in position, and the cap *b*³ may then be screwed into the body portion *a*, as will be readily 75 seen, and by means of this construction it will be seen that the thermometer *e*² may be readily removed either for sterilizing the same or in case of breakage to replace the same, and when the cap *b*³ is removed from the body 80 portion *a* the flange *c*³, being smaller than the internal screw-thread *a*², will not be displaced, and the thermometer will therefore remain firmly secured at all times.

Although I have shown the sleeve *c* as a 85 block of hard rubber or similar material, I do not limit myself to this construction, as the same may be made of stamped metal or other material, as may also the body portion *a* and the cap *b*³, and other changes in and modifications of the construction herein shown may be made without departing from the spirit of my invention or sacrificing its advantages.

Having fully described my invention, what I claim as new, and desire to secure by Letters 95 Patent, is—

1. A casing for a thermometer provided with an enlarged head, comprising a hollow body portion open at one end and internally screw-threaded at its open end, a hollow cap 100 provided with an externally-screw-threaded neck portion adapted to engage with the internal screw-thread of said body portion, said neck portion being also provided with an in-

ternal screw-thread and a sleeve provided with an external screw-thread adapted to engage with the internal screw-thread of said neck portion and a longitudinal opening into which the small end of the said thermometer is adapted to pass, substantially as shown and described.

2. A casing for a thermometer provided with an enlarged head comprising a hollow body portion open at one end and having a screw-thread at its open end, a hollow cap provided with an externally-screw-threaded neck portion adapted to engage with the internal screw-thread of said body portion, said neck portion being also provided with an internal screw-thread and a sleeve having an

external screw-thread adapted to engage with the internal screw-thread of said neck portion, said sleeve being also provided with a longitudinal opening therethrough into which the small end of the said thermometer is adapted to pass, and a plurality of longitudinal slots or recesses in the free end of said sleeve, substantially as shown and described.

In testimony that I claim the foregoing as my invention I have signed my name, in presence of the subscribing witnesses, this 12th day of August, 1902.

FRANK J. BERBERICH, JR.
